(57) **CLAIM**

The ornamental design for a collapsible tissue box holder, as shown and as described.

DESCRIPTION

FIG. 1 is a front perspective view of a receptacle of a collapsible tissue box holder showing my new design in its uncollapsed position;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the receptacle of the collapsible tissue box holder showing the receptacle of the collapsible tissue box holder in the collapsed position;

FIG. 9 is a bottom perspective view of the receptacle of the collapsible tissue box holder showing the receptacle of the collapsible tissue box holder in the partially collapsed position;

FIG. 10 is a front perspective view of the receptacle of the collapsible tissue box holder with an attached and removable lid;

FIG. 11 is a right view thereof of the receptacle of the collapsible tissue box holder with an attached and removable lid;

FIG. 12 is a left view thereof of the receptacle of the collapsible tissue box holder with an attached and removable lid;

FIG. 13 is a front side view thereof of the receptacle of the collapsible tissue box holder with an attached and removable lid;

FIG. 14 is a back side view thereof of the receptacle of the collapsible tissue box holder with an attached and removable lid;

FIG. 15 is a top view thereof of the receptacle of the collapsible tissue box holder with an attached and removable lid; and,

(Continued)

FIG. 16 is a bottom view thereof of the receptacle of the collapsible tissue box holder with an attached and removable lid.

The broken lines included in the Figures above represent unclaimed portions of the article and form no part of the claimed design.
